UNITED STATES PATENT OFFICE.

ALEXIS LE BLANC, OF NEW YORK, N. Y.

INTERRUPTER FOR ELECTROMAGNETIC RECIPROCATING DEVICES.

1,124,470.

Specification of Letters Patent.

Patented Jan. 12, 1915.

Application filed September 28, 1910. Serial No. 584,175.

To all whom it may concern:

Be it known that I, ALEXIS LE BLANC, a citizen of the United States, residing in the city of New York, in the county of New York and State of New York, have invented certain new and useful Improvements in Interrupters for Electromagnetic Reciprocating Devices, of which the following is a full, clear, and exact description, such as will enable others skilled in the art to which it pertains to make, construct, and use the same.

My invention relates particularly to magnetic interrupters or circuit breakers for use in connection with electromagnetic reciprocating devices, such as for instance, electromagnetic motors, riveting hammers, drills, and large gongs, in which solenoids are employed, provided with a core or plunger which is caused to automatically vibrate or reciprocate rapidly, whereby the interrupter is operated by the reciprocating core or plunger.

The object of my invention is to provide an improved magnetic interrupter or circuit breaker which will permit the current to be active for the maximum length of time for a given stroke of the movement of the plunger in order that the energizing current may have reached its highest point of efficiency when the circuit is interrupted, and the blow delivered, thus providing effective means causing extremely rapid interruption of the circuit to take place, and the same comprises a solenoid coil, a reciprocating core or plunger projecting into and movable under the influence of the coil, and a magnetic interrupter adapted to energize the coil and interrupt the current when the energizing current has reached its highest point of efficiency, said interrupter comprising a reciprocating magnetic contact and pivotally arranged, spring-pressed magnetic contacts.

I have shown my improved interrupter in connection with a riveting hammer, but it will be understood that it can be used in connection with numerous other appliances, wherein a powerful, rapid reciprocating device is required.

In the accompanying drawings forming a part of this specification, Figure 1 represents a sectional elevation of an electric riveting hammer embodying my invention, the handle of said hammer not being shown. Fig. 2 represents an end view of the same. Fig. 3 represents an enlarged side view of

the interrupter. Fig. 4 represents an end view of the same; and Fig. 5 represents a diagram of the wiring.

Similar letters of reference refer to like parts throughout the specification and drawings.

In the drawings, I have shown an electromagnetic reciprocating riveting hammer, in which a single solenoid and a single core is employed, in connection with my improved interrupter for making and breaking the electric circuit, whereby said core is caused to reciprocate rapidly. The device can and has been successfully employed in structures such as illustrated in my pending application Serial Number 496,823, filed May 18th, 1909, in which a plurality of axially aligned solenoids and an equal number of axially aligned cores are employed. The electric hammer is started by closing the circuit at the key, when the current will pass as indicated by the arrows (see Fig. 5), from the line to one of the contact arms to a contact plate arranged on the end of the core to another contact arm, and then about the solenoid, thereby drawing the core to its forward position in the solenoid, the pull of the core being against a retracting spring.

The spring, together with the momentum of the core, causes the core to return to its rearward position, and the magnetism set up in the coil, after current has been established by the core contacting with both of the contact arms, tends to cushion the plunger and its rearward stroke is arrested, and the magnetism in the coil draws the plunger forward to complete its forward stroke.

The solenoid may be constructed in any suitable manner, but as here shown, the coil a' is wound on a suitable spool b' made of insulating material. The spool b' is mounted upon the brass tubular bushing c' which is fitted into the circular soft steel end plates d' which are secured within a tubular soft steel casing e' provided with a tapered end. Slidingly mounted in the brass tubular bushing c' is the core or plunger b preferably made of soft steel and provided at its rear end with a contact plate e made of hardened steel or other magnetic material properly insulated from the core by the insulating disk e^2 which is secured thereto in any convenient manner. Owing to the action of the spiral compression spring g , the core b has a tendency to rotate, and for that reason, I prefer to construct the contact

plate *e* in the nature of a disk as shown, which construction enables the contact to rotate with the core thereby insuring perfect contact at all times between the contact plate *e* and the spring pressed contact arms *d* and *f*. A nose bushing *f'* is secured to the forward tapered end of the casing *e'*, in which may be secured a tool, not shown.

The core *b* at its forward end is provided with a reduced and hardened portion *g'* adapted to deliver the blow to the tool to be used. The core *b* is retracted by the spiral spring *g*, which is conveniently interposed between the end of the core and the inner side of the tapered end of the casing *e'*.

h is a block of insulating material, secured to the end plate *d'* in any convenient manner, as by screws *h'*. Mounted upon this block of insulating material *h* are the terminals *i* and *i'* and the steel brackets *j* and *j'* respectively, to which are pivotally secured the spring-pressed contact arms *d* and *f* made of hardened steel or other magnetic material. The bracket *j* is provided with a stop *k* at its forward end to limit the forward movement of the contact arm *d*. The contact arm *d* is provided near its upper end with a notch *d'* in which is secured one end of the spring *l*, the other end of which is preferably clamped between the steel bracket *j* and terminal *i*. Spring *l'* is secured in substantially the same manner to the insulating block *h*, the free end of the spring *l'* not being fastened to the contact arm *f*, but merely pressing against the same, in order that the contact arm *f* is constantly kept in contact with the contact plate *e* of the core *b*.

In the practical operation of the hammer, when the parts are in the position illustrated in full lines in Fig. 3, it is to be observed that the current flows from the feed wire *m* to the terminal *i*, then to the contact arm *d*, then through the contact plate *e* on the core and then from the latter to the contact arm *f* through the terminal *i'*, so as to effect the energization of the coil *a'*. This coil therefore exerts a strong pull upon the core *b*, so as to move the same forwardly in the casing *e'*, and impact the core *b* against the tool to impart the desired blow to the same. While the core is moving forwardly, (the parts being in neutral or normal position as shown in Fig. 3, namely, contact arms *d* and *f* in line with each other and both contacting with the contact plate *e*), it carries with it both arms *d* and *f* due to the magnetic attraction between the arms *d* and *f* and the magnetic contact plate *e*, until arm *d* strikes the stop *k* on the bracket *j* and is released from the contact plate *e*, when the contact is broken and no current is supplied and contact arm *d* instantly snaps back to its neutral posi-

tion, while contact arm *f* remains in contact with the contact plate *e*, and is carried with it to the forward end of the stroke. The retracting spring *g* and momentum of the core *b* causes the core to reach its rearward position, and while returning, the contact plate *e* contacts with the contact arm *d*, and the magnetism set up in the coil after current has been established again by contact plate *e* contacting with contact arm *d*, tends to cushion the core and its rearward movement is arrested, and the circuit being again closed, the magnetism in the coil draws the plunger forward to complete its forward stroke. It will thus be seen from an inspection of Fig. 3, in which contact arm *d* is shown in dotted lines with contact arm *f* in the same position, that the circuit is broken at or near the end of the forward stroke, namely, when said arm *d* engages with the stop *k* on the bracket *j* shown in dotted lines, when the same immediately snaps back into the position in which said arm *d* is shown in full lines, while contact arm *f* still contacts with the contact plate *e* due to the spring *l'* which keeps it in contact with the contact plate *e*, until the core has completed its forward stroke, when it returns with the core, and before reaching the full return stroke, the contact plate *e* on the end of the core strikes the contact arm *d*, which is in the position shown in full lines in Figs. 1 and 3, and carries it together with contact arm *f* back as illustrated in dotted lines in Fig. 3, thereby closing the circuit and thus the reciprocating motion of the core will continue so long as the key *c* remains closed. A condenser *n'* or other device may be inserted across the wires *m* and *n* to eliminate the spark when the circuit is broken by contact arm *d* as the core reciprocates.

It will be seen that from the moment the contact plate *e* contacts with the contact arm *d* on the backward movement of the core *b*, the current commences to rise in the coil *a'* and continues so to do until arm *d* moves to the rearward dotted position in Fig. 3, and the current still continues to rise until the contact arm *d* is released by the stop *k* on the bracket *j*. Thus it will be seen that current is rising in the coil for more than two-thirds of the cycle of operation of the core or plunger, thereby overcoming a large percentage of the self-induction of the coil *a'*, and enabling the magnetic circuit to rise to a higher degree of magnetic efficiency in the limited time that the core or plunger is performing its cycle of operation.

Experience has demonstrated that the organization above described is a practical and efficient one for accomplishing the ends sought by this invention. The construction may, however, be varied in detail by

those skilled in such matters, without departure from the invention.

I claim:

1. An interrupter for electromagnetic reciprocating devices, comprising a solenoid coil, a reciprocating core projecting into and movable under the influence of the coil, and a magnetic interrupter adapted to energize the coil and interrupt the current, said interrupter comprising a magnetic reciprocating contact movable with the core but insulated therefrom and a pair of spring-pressed magnetic contacts and means engaging with one of said spring-pressed contacts for breaking the circuit.

2. A device of the character described, comprising a rotary and reciprocatory contact of magnetic material secured to a reciprocating and rotary core, a solenoid coil adapted to influence the core to effect the movement thereof in one direction, means for moving the core in the opposite direction, supporting brackets mounted independently of the core, spring-pressed contact arms of magnetic material pivotally mounted in said brackets, one of said arms contacting with and reciprocating with the core in the direction of reciprocation thereof, the other contact arm contacting with the core but having a limited movement in the direction of the forward reciprocation of the core and arranged to impact against its supporting bracket to interrupt the current.

3. In an apparatus of the class described, in combination, an electromagnet, a reciprocatory element magnetically actuated thereby, an energizing circuit for the electromagnet, and a circuit making and breaking device, including a contact magnetically actuated by the reciprocatory element whereby to follow the same in one direction, a stop to arrest the contact at a predetermined point in its path, and means for moving the contact in the opposite direction after such arrest.

4. In an apparatus of the class described, in combination, an electromagnet, an energizing circuit therefor, a reciprocatory plunger magnetically actuated by the electromagnet, a magnetic contact plate movable with the plunger but electrically insulated therefrom and connected in said circuit, a contact adapted to bear on said plate and to be moved magnetically thereby, said contact being also connected with said circuit whereby separation of the contact and the plate will break the circuit, means for arresting the contact at a predetermined point in its path of movement, and means for moving the contact in the opposite direction after such arrest.

5. In an apparatus of the class described, in combination, an electromagnet, an energizing circuit therefor, a reciprocatory plunger magnetically actuated by the electro-

magnet, a magnetic contact plate movable with the plunger but electrically insulated therefrom and connected in said circuit, a contact finger adapted to bear on said plate and to be moved magnetically thereby in the forward direction, said finger being connected with said circuit whereby separation of the finger and plate will break the circuit, a stop to arrest the finger at a predetermined point in its forward movement, and means to move the finger rearwardly after such arrest.

6. In an apparatus of the class described, in combination, an electromagnet, an energizing circuit therefor, a reciprocatory plunger magnetically actuated by the electromagnet, a magnetic contact plate movable with the plunger but electrically insulated therefrom, a movable finger bearing on said plate, a spring operating to press the finger on the plate and cause the same to follow the plate, said finger being connected in said energizing circuit, a contact bearing on said plate and magnetically actuated thereby, said contact being connected with the circuit whereby separation of the contact and the plate will break the circuit, a stop to arrest the contact at a predetermined point in its path, and means to move the contact in the opposite direction after such arrest.

7. In an apparatus of the class described, in combination, an electromagnet, an energizing circuit therefor, a reciprocatory plunger magnetically actuated by the electromagnet, a magnetic contact plate movable with the plunger, and electrically insulated therefrom, a spring-pressed finger bearing on the plate and connected in said circuit whereby to carry current to the plate, a finger adapted to bear on the plate and magnetically actuated thereby so as to follow the plate, said last named finger being connected with the circuit whereby separation of the finger and plate will break the circuit, a stop to arrest the magnetically actuated finger at a predetermined point in its path of movement in one direction, and means for moving the magnetically actuated finger in the opposite direction after such arrest.

8. In an apparatus of the class described, in combination, an electromagnet, an energizing circuit therefor, a reciprocatory plunger magnetically actuated by the electromagnet, a contact plate movable with the plunger but electrically insulated therefrom, said plate being connected in said circuit, and means co-operating with the insulated contact plate to make and break the circuit thereat.

9. In an apparatus of the class described, a solenoid, a plunger movable thereby, an energizing circuit for said solenoid, a plurality of contact devices, said devices being magnetically actuated and one of said de-

125

130

vices having a resilient means adapted to supplement the magnetic action and maintain the contact in engagement with the plunger, the other of said devices having a 5 resilient means adapted to retract the contact from the plunger when the solenoid is deenergized, and a stop member adapted to break the magnetically induced contact of said last mentioned device with the plun-

ger, whereby the energizing circuit is broken 10 and the solenoid deenergized.

This specification signed and witnessed this 24th day of September, 1910.
